CLAIM

The ornamental design for a display screen with graphical user interface, as shown and described.

DESCRIPTION

FIG. 1 is a front view of a display screen with graphical user interface showing our new design;

FIG. 2 is a front view of a second embodiment of a display screen with graphical user interface;

FIG. 3 is a front view of a third embodiment of a display screen with graphical user interface;

FIG. 4 is a front view of a fourth embodiment of a display screen with graphical user interface; and,

FIG. 5 is a front view of a fifth embodiment of a display screen with graphical user interface.

The broken line showing of a portion of the display screen in all views is for the purpose of illustrating environmental structure and forms no part of the claimed design.
